UNITED STATES PATENT OFFICE.

EUSEBIUS J. MOLERA, OF SAN FRANCISCO, CALIFORNIA, ASSIGNOR TO
JOHN C. CEBRIAN, OF SAME PLACE.

DEVICE FOR MAGNETIZING THE TIRES OF DRIVE-WHEELS OF LOCOMOTIVES.

SPECIFICATION forming part of Letters Patent No. 288,356, dated November 13, 1883.

Application filed February 6, 1883. (No model.)

To all whom it may concern:

Be it known that I, EUSEBIUS J. MOLERA, of San Francisco, in the county of San Francisco and State of California, have invented 5 certain new and useful Improvements in Devices for Magnetizing the Tires of Drive-Wheels of Locomotives; and I do hereby declare the following to be a full, clear, and exact description of the invention, such as will 10 enable others skilled in the art to which it pertains to make and use the same.

My invention relates to an improvement in devices for magnetizing the drive-wheels of locomotives with the effect of causing their adhesion 15 to the track-rails, whereby said wheels can be utilized not only as brakes for retarding or stopping the locomotive on level tracks and downgrades, but also for assisting its progress on up or rising grades, the object of the 20 invention being to effect the above results by devices which shall apply the electrical energy to the greatest possible advantage, and which shall combine cheapness and simplicity of construction with durability and efficiency in use.

25 With these objects in view my invention consists in certain details of construction and combinations of parts, as will be hereinafter described, and pointed out in the claims.

In the accompanying drawings, Figure 1 is 30 a view, in side elevation, of a locomotive drive-wheel embodying my invention. Fig. 2 is a view thereof in vertical section. Fig. 3 is a view in perspective of one of the rings in which the commutator-plates are mounted. Fig. 4 is 35 a detached view of one of the said plates; and Fig. 5 is a view, in side elevation, of a drive-wheel embodying a modification of my improvement.

My improved drive-wheels are composed, 40 essentially, of electro-magnets A, which constitute the spokes, and of tires formed in segmental sections B, insulated from each other by non-magnetic blocks C, the legs of the magnets being respectively attached to the said tire-sections. The magnets A aforesaid are 45 grouped around a central hollow cylinder, D, in which the commutator-plates E and E' are mounted. The said cylinder is formed in any desired manner from suitable non-conducting 50 material, being T-shaped in cross-section, and having its external face or periphery divided into two sets or series of corresponding spaces,

F, by means of an intermediate circumferential flange, G', and ribs G, as shown. The spaces thus formed on the outer face of the cylinder, on one side of flange G', are occupied by the commutator-plates E, while the spaces formed on the other side of the flange are occupied by similar plates, E', the said plates E and E' being located directly opposite each other. The respective coil-terminals of the respective magnets A are connected to corresponding plates, E and E', substantially in the manner shown. Electricity for energizing the magnets is brought from a suitable source of 65 electric force carried by the locomotive by wires H and H', terminating in brushes I and I', suitably supported under and respectively arranged to be simultaneously engaged with corresponding plates, E and E'.

Having described the construction of my improved wheels, I will now set forth the method of their operation by reference to Fig. 1 of the drawings.

The wires H and H' are first connected with 75 the source of electric force. This done, as the wheel revolves, and it is immaterial in which direction, the plates E and E', connected with the coil-terminals of the magnet, having one or both poles in contact with the track-rails, 80 will simultaneously engage with the brushes I and I', with the effect of deflecting a current through the said magnet, the current flowing, in the direction indicated by the arrows, from the wire H to the brush I, through which it passes to the plate E, in contact with it, thence flowing through the coil of the magnet to the plate E', in contact with the brush I', from which it flows to the wire H' and completes the circuit in the battery. In the passage of 90 this current through the magnet its positive and negative poles will be magnetized and induce magnetism in the tire-sections to which they are respectively attached, these sections in turn inducing magnetism of opposite polarity in the track-rail, the attraction between the tire-sections and rails causing an adhesion of the wheel to the track. The current will be deflected through the magnet with the effects above stated until the commutator-plates 95 are carried beyond the range of the brushes by the rotation of the wheel, the brushes being almost immediately engaged with the pair of plates connected with the terminals of the coil of

the magnet to be next brought in contact with the rail. It will thus be seen that the action of the wheel is practically continuous as long as the wires H and H' are connected with the 5 source of electric force. In virtue of the arrangement above described the maximum effect of the current employed is obtained, inasmuch as it is applied to one magnet to the exclusion of the others.

10 The modified construction shown in Fig. 5 of the drawings differs from the construction shown in the other figures only in the construction and disposition of the commutator-plates, which, in the modified construction, 15 are segmental in form and grouped in two concentric rings, substantially as shown.

It is apparent that some changes in the construction and arrangement of parts may be resorted to. I would therefore have it understood 20 that I do not limit myself to the exact construction shown and described, but that I hold myself at liberty to make such slight changes and alterations as fairly fall within the spirit and scope of my invention.

25 Having fully described my invention, what I claim as new, and desire to secure by Letters Patent, is—

1. The combination, with drive-wheels having electro-magnet spokes and tires formed in insulated sections, the legs of the magnets being respectively attached to the said tire-sections, of separate commutators for the respective terminals of the coils of each magnet, and means for simultaneously connecting the plates to which the terminals of one magnet are connected with a source of electric force, substantially as set forth. 30

2. The combination, with drive-wheels having electro-magnet spokes and tires formed in insulated segmental sections, the legs of the 40 magnets being respectively attached to the tire-sections, of a non-conducting cylinder carrying on its periphery two series or sets of commutator-plates, and means for simultaneously connecting a pair of corresponding plates 45 with a source of electric force, substantially as set forth.

In testimony whereof I have signed this specification in the presence of two subscribing witnesses.

EUSEBIUS J. MOLERA.
